UNITED STATES PATENT OFFICE.

RICHARD O. ADAMS, OF LOUISVILLE, NEBRASKA.

TIMING APPARATUS FOR RACE-COURSES.

SPECIFICATION forming part of Letters Patent No. 402,291, dated April 30, 1889.

Application filed March 15, 1887. Serial No. 230,967. (No model.)

To all whom it may concern:

Be it known that I, RICHARD O. ADAMS, of Louisville, Cass county, State of Nebraska, have invented a new and useful Timing Apparatus for Race-Courses, of which the following is a full, clear, and exact description, reference being had to the accompanying drawings, forming a part hereof.

The object of this invention is to afford to the horse owner or trainer a sure and reliable means or method of determining the speed attained by a horse on the track, as well as a means of speeding horses at any desired rate.

The invention may be said to consist in a timing-instrument arranged to face the grandstand or amphitheater of a race-track, provided with one or more indicating-faces and devices controlled by an operator in the judges' stand or by an operator that is located at a distance from said instrument, for starting, stopping, and setting it back to the starting-point; and, further, in a series of timing-instruments arranged around a track at suitable distances apart, and suitable devices controlled by an operator in the judges' stand or by an operator that is located at a distance from said instruments for connecting them together, so that all may be started, stopped, and reset simultaneously or in unison.

In the drawings which illustrate the manner of carrying out my invention, Figure 1 is a plan view of a mile-track having my timing apparatus applied thereto. Fig. 2 is a face view of an ordinary horse-timer mounted upon a supporting-post. Fig. 3 is a side elevation of the same. Fig. 4 is a detail view of the operating-lever that is to be located in the judges' stand. Fig. 5 is a side elevation of an ordinary horse-timer mounted on a supporting-post, and showing the side of the supporting-bracket that is opposite to that shown in Fig. 3. Fig. 6 is a perspective view of a bell-crank having a depressing-arm for engaging the set-back pin of the timer. Fig. 7 is a like view of a bell-crank; and Fig. 8 is a detail view of the upper end of a supporting-bracket located on the posts, and showing the slot through which the arm for engaging the set-back pin operates.

A indicates the inside line of a mile race-course, around which the horses are supposed to travel in the direction of the arrows shown.

B is a timing-instrument, which may be of the ordinary construction, except of enlarged size, so as to be easily read from the grandstand, arranged to face such stand, and which can be provided with one, two, or three faces, as desired. The timer B is to be located on a suitable post just above the ordinary judges' stand of the track, and it, in connection with the timers B', form a series of timing-instruments, which are arranged upon suitable posts or supports at intervals around the track A. It is preferred that an instrument be located at each quarter of the track, as is here shown, although a greater or less number of them may be used, if so desired.

I may either connect the instruments forming the series by means of a wire or wires and start and stop and reset them by electricity, or I can use the mechanical devices here shown for the purpose. Of course in an arrangement of timing-instruments as described all of the instruments in the series should be started, stopped, and reset simultaneously. In the present instance this is accomplished as follows: A suitable hand-lever—such as F—to be operated by the starter, is located in the judges' stand. It is fulcrumed at G, and is provided with suitable stops on either side to limit its movement. The letter h indicates such stops.

The lever F is pivoted to some part of the judges' stand—say a post, D—and a wire, a, is attached to one of its ends and passes out and up to a bell-crank—such as d—located on the lower portion of the supporting-bracket C', thence to the starting and stopping attachment of the timer B, thence to another bell-crank, d, located on the upper portion of the supporting-bracket of the timer B, thence to a post, E, which may carry a suitable roller or pulley for changing the direction of strain, and thence to the first one of the series of timers B' arranged around the track, as before mentioned. The wire a, after leaving the devices at the judges' stand, engages a supporting-post, E, and then passes to the bell-crank located on the lower portion of the bracket which supports the first timer of the series, thence to its starting device, and so on with each of the timing-instruments, all of them being arranged substantially alike and supported upon posts C so as to face the

drivers of the horses as they travel around the track.

For the purpose of resetting all of the instruments simultaneously another lever such as F will be provided, and another wire, a', will be arranged in a manner similar to the first-mentioned one, except that it will engage bell-crank or equivalent devices located on the opposite sides of the brackets 10 which support the timers, and the bell-crank d', that is located at the upper portion of this side of the bracket, will be or is provided with a laterally-projecting arm, d'', which extends from one side thereof through slot 14 in said bracket in position to engage the set-back pin 12, as shown.

All of the instruments B B' are to be of such size that their faces c may be read by the drivers traveling around the track.

20 The operation of the invention is as follows: When a race is to be started, the starter first throws the lever F to one side, (or a lever that is similar in construction to it,) thereby operating the wire a' and depressing the arm d'' of bell-crank d' and setting all of the instruments back to zero; then at the instant of the start the operator throws over the other lever, and thereby draws down the starting device 10 of the instruments and starts them 25 all simultaneously. For the purpose of stopping the instruments at the finish of the race the starting-lever is to be thrown in an opposite direction, thereby raising the device 10 on the side of the instruments. The construction and operation of ordinary horse-timers is so well known that I do not deem a description of them necessary to be given here.

30 For the purpose of returning the stopping and starting and resetting devices to their

original position after they have been moved 40 in one direction it will be necessary to provide a suitable spring or a weight of some kind at the end of each wire, so as to hold them taut at all times, or a double set of wires can be provided for such purpose similar to those here 45 indicated. These changes in the details of construction, together with any others that might suggest themselves to a skilled mechanic, could be made without departing from the spirit of my invention.

50 Having thus described my invention, what I claim is—

1. In a timing mechanism for race-courses, the combination of an operative timing-instrument mechanically mounted so as to 55 be visible to the general class of spectators at a race-course, and controlling-connections between said timing-instrument and a distant operating-point, whereby said instrument may be started, stopped, and otherwise 60 controlled by an operator located at a distance from said timing-instrument, substantially as shown and specified.

2. In a timing mechanism for race-courses, the combination of a series of operative timing-instruments arranged at intervals around the course and facing the direction of advance, and devices, substantially as described, arranged to control, stop, and start each timing-instrument of the series simultaneously, 65 substantially as shown and specified.

In testimony whereof I affix my signature in presence of two witnesses.

RICHARD O. ADAMS.
